COMBINED WET SCREENING AND SHREDDING APPARATUS

William C. Laughlin, New York, N. Y., assignor
to Ralph B. Carter Company, Hackensack,
N. J., a corporation of New York

Application August 3, 1945, Serial No. 608,647

2 Claims. (Cl. 210—152)

1

This invention relates to screening out the oversized material from a flow of sewage or industrial waste with subsequent shredding of the screened out material.

The object of the invention is to reduce the oversize solids entrained in flow to avoid entangling of rags and strings in the raking mechanism of sedimentation tanks, and clogging of pumps and pipe lines, and permit of more rapid digestion of the organic solids in the subsequent sewage treatment.

The apparatus consists primarily of a travelling belt made up of standard roller chain, such as is used for power purposes, of any desired length or width, wherein there are openings between the links which allow liquid to pass while retaining the oversize solids, but having links with cutting edges forming a part of the travelling belt and extending above the surface of the other links. Then, with this belt travelling, and sewage passed to its surface, the liquid with small solids passes through the openings of the belt and the oversized solids move with the belt, and away from the screening locality, and there meet a comb of a series of teeth (or series of combs), spaced so that the teeth of the belt pass through the teeth of the comb with scissor clearance, and the cooperating cutting edges cause a shredding of the oversize solids when shreddable; the comb yielding when so cutting. The comb is displaceable to permit oversize unshreddable solids to pass without injuring the cutting edges.

The invention consists of a means of screening out the oversized material from a flow of sewage or industrial waste, meanwhile conveying the oversize and screened out material to a point above the liquid flow of the sewage, and there subjecting it to a shredding action to reduce it to small size by means of cutting teeth, and then allowing the shredded material to pass again to the sewage flow for subsequent sedimentation of the solids in the subsequent sewage treatment.

The invention will be further described, an embodiment thereof shown in the drawings, and the invention will be finally pointed out in the claims.

In the accompanying drawings,

Fig. 1 is a side view of a screener and shredder;
Fig. 2 is a sectional plan view with a section taken on line 2—2 of Fig. 1;

Fig. 3 is a side view of the essential parts of the screener and shredder shown in the path of the sewage flow;

Fig. 4 is a detail section taken on line 4—4 of Fig. 3;

2

Fig. 5 is a detail section taken on line 5—5 of Fig. 4;

Fig. 6 is an enlarged view of the links;

Fig. 7 is a fragmentary perspective view of the screener and shredder;

Fig. 8 is a detail plan view, taken on line 8—8 of Fig. 4, and

Fig. 9 is a detail view of an alternate form of cutting links showing square cutting edge.

Similar characters of reference indicate corresponding parts throughout the various views.

Referring to the drawings, and more particularly to Fig. 1, the sewage flow channel 10 has a descending portion 11, terminating in a lower flow channel 12.

10 A frame 15 consists of vertical bars 16, horizontal bars 17 and diagonal bars 18. A motor 20 with a sprocket wheel 21 is supported upon the horizontal bars 17, and has a roller chain 22 for 20 a larger sprocket wheel 23 on a shaft 24 supported in bearings 25, in turn supported on two parallel diagonal bars 18, one on each side of the frame 15. The bearings 25 are clamped to the diagonal bars 18 by bolts 26, and are adjustable 25 in position by adjusting bolts 27.

25 On the shaft 24 are a plurality of sprockets 28. Above the diagonal bars 18, and at the lower ends of the same, a similar shaft 29, with a plurality of sprockets 30, is supported in bearings 31, which are clamped in position by bolts 32. This shaft 29 with sprocket 30 is below the descending channel 11.

30 Over the sprockets 28 and 30 passes the improved screener and shredder 35.

35 This screener and shredder consists of a plurality of spaced and parallel rods 36, having spaced collars 37 separated by connecting links 38 and shredder links 40 forming a belt conveyor. The links 38 are thus spaced from each other and permit the flow of fluid between the same.

40 The shredder links 40 are also spaced from each other and permit the flow of fluid between the same. The combined links act as a screen to permit the flow of liquid, but prevent the passage of rags, etc., or other oversize materials from passing with the liquid through the spaces between the links. These oversized materials are drawn along and transported by the moving screen, out of and away from the sewage flow path.

45 The shredder links 40 consist each of a body portion 41, and of an upwardly extending cutting portion 42. This portion 42 has its front part 43 inclined to provide a cutting edge 44, or a straight edge 43 as in Figure 9.

50 55 In the path of the shredder links 40, a comb

45 is disposed, which consists of a transversely arranged bar having spaced teeth 46. One of these combs is shown, but a plurality of such combs spaced from each other in parallel portions may be used. The comb 45 is supported on a yoke 47 fulcrumed on a shaft 48, to permit the raising of the yoke 47 should any nail or other metallic solid which cannot be cut or shredded, impinge against the comb when carried along by the shredder links 40, the nail then passing through the space formed by the raising of the comb. The comb 45 may be adjusted by screws 49 resting on the supporting projection 50, supported by a frame vertical bracket 16. Each of the teeth 46 is provided with a cutting edge 52. The comb 45 is fastened by screws 51 and set screws 51a to a crosspiece 53 of the yoke 47. The shaft 48 is supported by bearings 54 supported in turn by vertical bars 15a.

The foregoing frame with combined screener and shredder 35 is placed in a widened part 55 of the channel 12 as shown in Fig. 2, so that the combined screener and shredder 35 is placed at an inclined position transverse to the sewage flow, indicated by the arrows 56, the screener and shredder 35 moving in the direction of the arrows 57 as shown in Fig. 3. The lower portion acts as a screener and the upper portion acts as a shredder. The laterally arranged links 40 bridge the sewage flow so that all the fine solids and liquor of the sewage pass through the lower screening portion and the oversized material is conveyed to the upper shredder portion.

As the sewage which invariably contains rags, or the like, which interfere with the sedimentation process passes on to the screener and shredder 35, the fluid passes through, but the rags and other oversize material are moved up and out of the sewage flow, until decimated by the cutting action, when the threads, etc. are returned to the sewage flow, the decimated threads or trash not interfering with the sedimentation methods.

I wish to be understood that I do not desire to be limited to the exact details of construction shown and described, for obvious modifications will occur to a person skilled in the art.

I claim:

1. In a combined wet screening and shredding apparatus, the combination with a continuous

belt conveyor having laterally spaced and end pivoted links, pusher abutments on said links, cutting edges on the forward parts of said pusher abutments, means supporting one end of the conveyor above the other end to present an inclined surface to the horizontal, and a comb transversely disposed to the conveyor having cutting edges complementary to the cutting edges of the conveyor links, and above the upper end of the conveyor, of a yoke for supporting the comb, a pivotal support for one end of the yoke at one side of the comb, and a support for the other end of the yoke at the other side of the comb.

2. In a combined wet screening and shredding apparatus, the combination with a continuous belt conveyor having laterally spaced and end pivoted links, pusher abutments on said links, cutting edges on the forward parts of said pusher abutments, means supporting one end of the conveyor above the other end to present an inclined surface to the horizontal, and a comb transversely disposed to the conveyor having cutting edges complementary to the cutting edges of the conveyor links, and above the upper end of the conveyor, of a yoke for supporting the comb, a pivotal support for one end of the yoke at one side of the comb, and a support for the other end of the yoke at the other side of the comb, of means supporting said comb in a yielding manner to pressure exerted by any object being cut by the conveyor cutting edges and comb, and displaceable to permit oversize unshreddable solids to pass without injuring the cutting edges.

WILLIAM C. LAUGHLIN.
